UNITED STATES PATENT OFFICE

93,443

DESIGN FOR A PIE BAKING PAN

Frederick W. Birkenhauer, Newark, N. J.

Application June 18, 1934, Serial No. 52,225

Term of patent 14 years

To all whom it may concern:

Be it known that I, FREDERICK W. BIRKENHAUER, a citizen of the United States, and a resident of Newark, in the county of Essex and State of New Jersey, have invented a new, original, and ornamental Design for Pie Baking Pans, of which the following is a specification, reference being had to accompanying drawing, forming part thereof.

I claim:

The ornamental design for a pie baking pan as shown.

FREDERICK W. BIRKENHAUER.
